UNITED STATES PATENT OFFICE.

SAMUEL T. THOMAS, OF LAWRENCE, MASSACHUSETTS.

LOOM.

Specification of Letters Patent No. 13,187, dated July 3, 1855.

To all whom it may concern:

Be it known that I, SAMUEL T. THOMAS, of Lawrence, in the county of Essex and State of Massachusetts, have invented an Improved Loom for Fancy Weaving; and I do hereby declare that the same is fully described and represented in the following specification and the accompanying drawings, letters, figures, and references thereof.

10 Of said drawings, Figure 1, denotes a top view of my improved loom; Fig. 2, a front elevation of it; Fig. 3, an elevation of the right end of it; Fig. 4, an elevation of the left end of it; Fig. 5, a rear elevation of it; Fig. 6, is a vertical and longitudinal section of it, the same being taken through the cam shaft C, to be hereinafter described; Fig. 7, is a transverse and central section of such loom, it being taken so to exhibit 20 the parts on the left of the plane of section; Fig. 8, is a vertical and longitudinal section of the cam shaft C, and the cam for operating the shuttle boxes. Fig. 9 is a vertical and transverse section of the detached balance wheel and its friction clutch wheel to be hereinafter described.

In the drawings, A, is the main frame of the loom.

B is the main driving shaft; C, the cam shaft; D, the lay; E, the breast beam; F, and G, two series of movable shuttle boxes (applied to opposite ends of the race beam) and H, H, H, are the harnesses or bars to represent them—the front two harnesses or bars being employed for the plain selvage or stripe weaving, while the others are for fancy weaving. Each of the said harnesses is supported by four cords I, I, two of which extend vertically and are made to pass 30 against and horizontally over two friction sheaves or pulleys K', K' arranged at the upper part of the loom as seen in the drawings. From thence these cords are united or fastened to the upper end of one of a series 40 of rocker levers L, L, disposed as seen in Figs. 1, 2 and 6, the lower arm of said lever being fastened to two other cords I', I', which pass horizontally from and under and against pulleys K², K³, and thence up 45 to the harness. Each harness by such an arrangement of pulleys and cords is caused when its rocker is moved upon the fulcrum M, thereof to play in a vertical plane.

From each rocker lever L, an arm N, extends as seen in Figs. 2, and 6, and carries a 50 projection or friction roller, which extends

into a cam groove a, made in a rocker sector, O, arranged and made to turn on a fulcrum or shaft P, as seen in the drawing. The periphery of this rocker sector is serrated and engages with a toothed neck b, formed upon the lower end of the lifter or bar R, arranged and formed as seen in Figs. 1, 4, and 6. The series of lifters R, R, operates in connection with an elevator S, and 60 a depressor, T, which are bars projecting respectively from two vertical sliding shafts V, W, disposed as seen in Figs. 1, 4 and 5.

A reciprocating movement is imparted to each of the shafts V, W, (they at the same 70 time being moved in opposite directions) by means of cranks and connecting rods arranged as seen at X, Y, and Z, Q, in Figs. 2, 4 and 5. A horizontal shaft, c, carries the said two cranks X, Y and is driven by 75 two gears d, e, applied to it and the main driving shaft as seen in the drawings, and particularly in Fig. 4.

Each of the lifters R, has applied to it a bent lever f, as seen in Fig. 6, said bent 80 lever being made to play vertically upon a horizontal pin or fulcrum g. The lower or the shorter arm of said lever rests against the lifter or is borne against it by the gravitating power of a weight h, (or the 85 equivalent thereof) fixed to the longer arm. There is a small pin or stud i, projecting from the longer or horizontal arm of each lever f, the series of pins being made to operate in connection with a jacquard prism 90 k, and a pattern card chain, l, which are arranged as seen in the drawings and are moved either upward or downward so as to carry them either toward or away from the series of levers as occasion may require. 95 Such movements of the pattern prism may be effected by means of any suitable mechanism; that which I employ consisting of a horizontal rocker shaft, which sustains the journals of the pattern prism by means of 100 arms n, n, and has a third arm, o, projected backward from it (as seen in the drawings) and jointed to the upper end of a connecting rod P, whose lower end is jointed to a crank, q, fixed upon the end of the main 105 driving shaft B.

By means of the jacquard pattern prism and card (which may be put in rotation by any suitable mechanism and operated at proper periods,) the series of bent levers 110 f, f, the series of lifters R, R, the series of reciprocating rocker sectors O, O, the cams a,

and the arms N, N, of the rocker levers L, L, the movements of the harnesses are regulated so as to dispense with a great deal of unnecessary motion to which they are subjected in most other fancy looms, and which has a tendency not only to produce a wear of them, but a corresponding wear of the warps.

The mechanism in other fancy looms is so 10 constructed as to close all the warps together at or during every beat of the lay and previous to the elevation and depression of such of them as were to be employed for the next throw of the shuttle. This 15 movement or mixing together of all the warps is not effected by or in my machine, for those warps, which have been either elevated or depressed, are maintained stationary either up or down, as the case may 20 be when the lay beats up. Each warp thread will thus remain stationary until it becomes necessary to move it and no matter what may be the number of the beats of the lay in the interim. By such a mode of operating 25 the harnesses and maintaining them at rest much wear of them and the warps is prevented,—such a result being effected by the employment of the rocker sector and its grooved cam in connection with the arm of 30 the rocker lever and with the lifter substantially in manner as set forth. I would also observe that not only by combining with the pattern prism and the lifters, the bent levers arranged with respect to the same as above 35 described; but by giving to said pattern prism, vertical or up and down instead of horizontal motions (as pattern prisms of a jacquard apparatus are generally operated) a very important result is effected, for when 40 a pattern prism is moved horizontally in the usual way it is found very difficult to maintain the working leaf of the cards in contact with the working face of the prism, as both face and leaf stand in vertical, or nearly 45 vertical positions. Such positions of them require a bar or some other contrivance so applied to the pattern chain as to keep it in contact with the working face of the prism otherwise the wires are liable to miss their 50 hold of the pattern cord and produce a false movement of the harnesses or warps.

In my improved loom the gravitating power of the pattern chain is employed to maintain its working leaf in close contact 55 with the working face of the pattern prism, which is always uppermost. In order that the lifters may operate to advantage, I arrange each of them at a slight inclination from the vertical and in a direction toward 60 its bent lever, f. Under such an arrangement of the lifter its gravitating power will generally, be sufficient to effect its movement in a direction toward the lever whenever occasion may require, but in case, such gravitating power may not be sufficient to

produce such an effect particularly when the loom is running at high speed, a small spring may be applied to each lifter so as to insure its movement in the direction required. The cords of each of the front two harnesses 70 are led around guide pulleys r, s, and vertically toward and are fastened to the end of one of two levers t, u, see Figs. 1, 2 and 7, these levers at their rear ends turning vertically upon a fulcrum U. Each of said 75 levers is moved in a vertical plane by means of a cam W' or X', fixed upon the cam shaft C, said cam shaft being made to receive its motion from the main driving shaft by means of a train of gears y, and z, see 80 Figs. 1, 3 and 5.

Each of the cams W' and X', is formed with a cam groove made in one side of it, and for the purpose of receiving a stud or friction roller projecting from the lever t, 85 or u, immediately adjacent thereto. The cam has a continuous rotary motion imparted to it, its groove being so formed as during such to give to the lever such an upward or downward motion, and interval or 90 intervals of rest, as may be necessary to insure the correct operation of the harness.

In the mechanism last described only one lever and cam are employed to operate a harness, whereas by the ordinary method of 95 moving a harness with treadles and a cam, two treadles and two cams become necessary.

Each set F, G, of movable shuttle boxes, hereinbefore mentioned is sustained upon the upper end of a rod a', which is supported so as to slide freely, upward and downward and is connected to a lever c' by means of a link b', jointed to both. The said lever c' at its rear end is jointed to another lever d', and near the fulcrum e', thereof, as seen in Figs. 3 and 4. The lever d', has vertical movements imparted to it by means of a star cam f', which turns upon a long horizontal shaft g', extending through both ends of the loom. Between the two 100 levers c', d', is a wedge h', which is affixed to one side of a slide bar i', which slides freely in bearings fixed to the lower lever d'. 105

Against a projection k', from the inner side of the slide bar, i', a stud l', extended 110 from a lever m', or n', (see Figs. 5 and 6,) is caused to bear one of these levers, viz., m', or that situated at the right end of the loom, turns freely on a horizontal shaft o', the other lever n', or that situated at the 115 other end of the loom being affixed to said shaft. Thus it will be seen that one lever operates independently of the other.

In Fig. 10 I have exhibited a top view of the mechanism that is situated below the 120 main driving shaft B, and on the left end of the loom, and in this view, as well as in Fig. 2, are shown two star cams p', q', which are shaped precisely alike, one of them being exhibited in side view in Fig. 11. 125 130

These cams are also represented in Fig. 8. They are for the purpose of operating the levers m' , n' . The periphery of one of them, viz., p' , rests against an arm r' , projecting from the lever n' , while the periphery of the other cam q' , works in contact with a curved arm s' , fixed to, and extending from the shaft o' . Each of the continuous star cams f' , p' , q' , on the left side of the machine revolves freely on its shaft g' and has a friction pulley or barrel t' , affixed to one side of it, there being a friction brake or strap u' , extended around and against the periphery of the barrel and serving to maintain the star cam in any position into which it may be turned by its pawl and ratchet, each of said continuous star cams being provided with a ratchet as seen at w' , x' , y' . Besides the ratchet above mentioned there is another ratchet z' , which is fixed upon the shaft g' , and is for the purpose of putting said shaft in rotation. The several ratchets are respectively furnished with sliding impelling pawls a^2 , b^2 , c^2 , d^2 , which are arranged as seen in Figs. 4 and 10, each pawl being provided with a standard e^2 , which rises above the pawl and in front of the lower arm of a rocker lever f^2 , whose upper arm rests in contact with the periphery of a cam g^2 , fixed upon the cam shaft C. To each pawl there is also applied a retractive spring h^2 , the rear end of each pawl being provided with a notch or shoulder as seen at i^2 , which is intended to operate in connection with one of a series of upright and bent wires k^2 , which are supported so as to slide freely in vertical directions through guides l^2 , m^2 , the upper parts of these wires are curved semicircularly and operate in connection with a pattern prism n^2 , and pattern card chain o^2 , arranged as seen in the drawings. The shaft of this pattern prism projects vertically from a slide rod p^2 , from which an arm q^2 extends toward and rests upon a cam r^2 , fixed upon the driving shaft. This cam serves to elevate the slide rod and its pattern prism, while a spring s^2 , fixed upon the rod and bearing against a projection t^2 , through which the rod slides, serves to depress said rod and said pattern prism. Whenever any one of the wires k^2 , drops into a hole of its pattern prism, its lower end will be so carried below the top of the shoulder i^2 , of its pawl as to prevent said pawl from being retracted by its spring and carried into contact with the rocker lever f^2 .

During the rotation of the cam g^2 , such of the impelling pawls a^2 , b^2 , c^2 , d^2 , as may have their posts or standards in contact with the rocker lever f^2 , will be driven forward and will turn their ratchets so as to rotate their respective star wheels, the order or periods of such rotation being governed by the pattern prism and its chain o^2 .

The above described machinery not only causes each series of shuttle boxes to be operated independently of the other and so that it may be moved to any desirable extent, while the other is either stationary or put in movement, but it serves to cause either of the series of shuttle boxes to be moved (whenever such may be necessary) double the distance of the other in the same length of time. This latter movement of either series of shuttle boxes is produced by its star cam f' , and the wedge h' , over the same, the said wedge during the time the star cam is elevating the lever d' being forced or moved between said lever d' and the lever c' , over it, so as, in connection with the star cam, to produce a compound movement of the lever c' , and the series of shuttle boxes immediately connected with it.

My improvement enables me to use five shuttles in two series of boxes in which there are three boxes in each series, whereas where two such series of shuttle boxes are so connected by mechanism that their movements in opposite directions are alike, the movement of the one being dependent on that of the other, and controlled by the same mechanism only three shuttles could be employed in them. Thus it will be seen that my method of operating the two series of shuttle boxes by two mechanisms independent of one another and controlled by one jacquard apparatus situated at one end of the loom possesses an important advantage comparatively speaking.

On the main driving shaft B, there is placed a fly or balance wheel u^2 , it being so applied to the shaft as to be capable of free rotation thereon, such balance wheel and the friction clutch wheel with which it acts is shown in section in Fig. 9. The latter wheel v^2 , is fixed firmly to the main shaft and has a conical surface or periphery w^2 , which extends from it and enters a corresponding recess x^2 , made within the balance wheel.

The neck of the balance wheel is provided with a groove y^2 , which extends around it and receives a forked rocker lever z^2 , see Figs. 1, 2 and 3. The fulcrum shaft of said lever being supported by two struts a^3 , a^3 , projected from the end of the frame work. The shaft b^3 , of the shipper c^3 , is connected with the rocker lever z^2 , by means of a third rocker lever d^3 , and so that when the shipper moves toward its holding notch or shoulder e^3 , it shall cause the detached balance or fly wheel to be moved toward and against its friction clutch wheel, a spring f^3 , upon the shaft of the shipper serving to produce a contrary movement of the fly wheel when the shipper is thrown off its shoulder. The detached fly wheel may not only serve as a fly but also as a pulley for the driving belt of the loom to run upon.

The object of having a fly or balance wheel applied to the loom in the above described manner, is to enable the loom whenever it is set in motion to be started with a force sufficient to throw the shuttle with certainty across the race beam which cannot always be effected where the loom is to be put in operation by slipping the driving belt, from a loose to a fast pulley, applied 5 to its driving shaft and said shaft has a fly wheel fastened to it. A further object of the detached fly wheel, and the mechanism for moving it on the main shaft is to so separate the said fly wheel from the driving shaft just prior to a stoppage of the loom in order that the loom may be relieved of the momentum of the fly wheel which were the motion of the fly suddenly arrested would not only produce a 10 great and injurious strain on the working parts of the loom, but other disadvantageous results. The friction clutch prevents the momentum of the fly from straining or doing injury to the mechanism set in operation by it.

To the periphery of the friction clutch v^2 , a friction brake g^3 , is applied as seen in Figs. 1 and 3, such friction brake being provided with a lever latch h^3 , which turns 15 horizontally on or in the brake as a fulcrum and is jointed to an upright lever i^3 whose lower arm is bifurcated and made to straddle a projection k^3 , extending from the shipper shaft, the same being as represented 20 in Fig. 2. When the shipper is thrown from its notch, the hook of the lever latch h^3 will be moved up against the side of the clutch wheel v^2 , and will catch upon a projection or stud i^4 , fixed upon the same as seen in 25 Fig. 12, which represents an inner side view of the clutch wheel.

The object of the brake g^3 , the latch h^3 , and stud i^4 , is to prevent the loom from making a false pick, immediately after the 30 filling fork or weft stop motion has been put in operation which otherwise would invariably take place.

Having thus described my improved loom what I claim is as follows:

50 1. I claim combining with each rocker lever L , and the lifter R , thereof, an arm N , cam a , and sector O , or the equivalent or equivalents thereof, the whole being applied together and made to operate in the manner 55 essentially as specified.

2. I also claim combining with the series of lifters R , R , and the pattern prism k , a series of bent levers f , f , or their equivalents,

and imparting to the pattern prism vertical, or up and down movements as described, the 60 same being to produce advantages as stated.

3. I also claim when the upper and lower sets of cords of a harness are supported by pulleys as described, applying both said upper and lower sets of cords to one and 65 the same end of a lever operated by a cam having a continuous rotation as described.

4. I also claim, combining with the star cam and lever for moving a set of shuttle boxes a mechanism substantially as described for imparting an accelerated movement to the set of shuttle boxes as explained, the said mechanism consisting of the additional lever d , the movable wedge h' , and its operative mechanism as described. 70

5. I also claim the above described arrangement of a jacquard, the wires thereof, the impelling pawls, and the star cams and their shafts, whereby one jacquard apparatus applied at one end of the loom, is 80 made to operate two independent shuttle motions of the loom as explained.

6. I also claim so applying to the main shaft a friction clutch wheel, and a fly or balance wheel that the fly may run loosely 85 upon the shaft and be capable of being moved either toward or away from the friction clutch, in combination with so connecting the fly with the shipper that the said fly shall be moved laterally during and by 90 the movements of the shipper as described.

7. I also claim, combining with the friction wheel and the shipper as described a brake mechanism for throwing said brake 95 g^3 , into and out of operation as specified, such mechanism consisting of the lever latch h^3 , the projection k^3 , and spring f^3 , as specified.

In testimony whereof, I have hereunto set my signature this seventh day of April A. 100 D. 1855.
